DESIGN FOR A SPOON OR ANALOGOUS ARTICLE

Arthur Le Roy Barney, New York, N. Y., assignor to Tiffany & Company, New York, N. Y., a corporation of New York

Application May 19, 1937, Serial No. 69,437

Term of patent 14 years

To all whom it may concern:

Be it known that I, Arthur Le Roy Barney, a citizen of the United States, residing at, and whose post office address is, No. 64 East 86th Street, New York city, New York, have invented a new, original, and ornamental Design for a Spoon or Analogous Article, of which the following is a specification, reference being had to the accompanying drawing, forming a part thereof.

I regard the dominant feature of my design as being the contour and ornamentation of the handle thereof and as being in the combination of this particular shaped handle with an entirely round bowl as shown.

I claim:

The ornamental design for a spoon or analogous article as shown and described.

ARTHUR LE ROY BARNEY.
